Filed Aug. 11, 1975, Ser. No. 603,550

Term of patent 14 years

Int. Cl. D6—99

U.S. Cl. D6—124

FIG. 1 is a front elevational view of a rack for blankets or the like showing my new design, the side opposite being identical except for the showings of the upper and lower ends of the vertical support member.

FIG. 2 is a right side elevational view thereof.

FIG. 3 is a left side elevational view thereof.

FIGS. 4 and 5 are enlarged sectional views taken respectively on the lines 4—4 and 5—5 of FIG. 1.

FIG. 6 is a bottom plan view of a fragment thereof.

I claim:

The ornamental design for a rack for blankets or the like, substantially as shown and described.
